UNITED STATES PATENT OFFICE.

WILLIS S. FARNSWORTH, OF SAN FRANCISCO, CALIFORNIA, ASSIGNOR TO COIN CONTROLLED LOCK CO., OF SAN FRANCISCO, CALIFORNIA, A CORPORATION OF CALIFORNIA.

LOCK FOR LOCKERS.

1,114,244.

Specification of Letters Patent. Patented Oct. 20, 1914.

Application filed November 9, 1912. Serial No. 730,381.

To all whom it may concern:

Be it known that I, WILLIS S. FARNSWORTH, a citizen of the United States, residing in the city and county of San Francisco and State of California, have invented new and useful Improvements in Locks for Lockers, of which the following is a specification.

This invention relates to an umbrella lock.

The invention primarily resides in an umbrella receptacle, a closure therefor, and means for locking said closure.

The invention further consists of the parts and the construction and combination of parts as hereinafter more fully described and claimed, having reference to the accompanying drawings, in which—

Figure 1 is a view partly in elevation and partly in vertical section, of one form of the invention. Fig. 2 is a vertical section. Fig. 3 is a detail section of the locker closure and the locking means thereon.

I employ a series of umbrella receptacles A, preferably formed of wire mesh 2, mounted on a suitable framework 3, revolvably mounted on a standard 4; roller bearings 5 being provided to facilitate the rotation of the umbrella receptacles on the standard 4. The lower ends of the receptacles A are open, and extending beneath the open lower ends of the receptacles A and mounted on the framework 3, is an annular trough or drain 6, for receiving the water drained from the umbrellas in the receptacles A.

In the form of the invention shown in Figs. 3 and 4, the receptacles A are rigidly mounted on any suitable support B, such as a wall; a number of receptacles A being adapted to be placed in a row, as shown in Fig. 3.

The receptacles A are provided with closures 7 at their upper ends, which are hinged at 8 to swing in a vertical direction. Reciprocally mounted on the underside of the closures 7 are bolts 9, which extend approximately the length of the closures 7, and are adapted to engage the edge of the opening in the frame 3 surrounding the closures 7, as particularly shown in Fig. 5.

The bolt 9 is designed to be normally held against retraction when the closure is in its closed position, by means of a spring pressed pin 10, reciprocally mounted in the upper inner portion of the frame 3 which

in turn is designed to be held against rearward movement by means of a lock bolt 11, of any suitable construction. The lock bolt 11 is here shown as operated by means of a lock 12, of any suitable description, preferably of that type of lock in which the bolt 11 is reciprocated by the rotation of a lock cylinder 13.

The bolt 11 is designed to be moved in front of the rear end of the pin 10, while the bolt 9 is in engagement with the frame 3, as shown in Fig. 3, thereby preventing the bolt 9 and pin 10 from being retracted, so as to lock the closure 7 in its closed position.

When it is desired to use one of the lockers, an umbrella or parasol is placed in the receptacle A with its lower end resting in the drain plate 6. The closure 7 is then shut to cause the bolt 9 to be thrown in locking engagement with the frame 3. The lock 12 is then operated to throw the bolt 11 rearward of the spring pressed pin 10 to hold it against retraction, thereby effectually locking the closure 7 in its closed position and preventing the removal of the umbrella or parasol from the receptacle A.

The lock 12 is preferably of that character in which it is necessary to insert a coin in a coin slot 14 in order to operate the lock to throw the bolt and remove the key, thus necessitating the depositing of a coin before a locker may be used.

In the operation of the invention a key is inserted in the lock, whereby the bolt 11 may be retracted and moved out of the path of travel of the spring pressed pin 10. An upward pull is then exerted on the closure 7 in such manner as to rock it on its hinged mounting 8. This upward movement of the closure 7 carries the outer end of the bolt 9 to ride over the edge of the opening in the frame 3, thereby moving the bolt 9 longitudinally in opposition to the spring pressed pin 10, which is free to move in a rearward direction after the bolt 11 has been retracted. This allows the closure 7 being readily opened to give access to the interior of the umbrella receptacle A.

To facilitate the disengagement of the bolt 9 from the edge of the frame 3, the former is provided with a rounded outer end which will readily ride over the edge of the opening in the frame 3, when the closure 7 is being opened or closed.

A coin chute or receiver 15 of any suit-

110

able description is provided in the locker for the reception of the coins deposited in the locks 12. These coin chutes 15 may lead to any suitable coin receptacles disposed at 5 any convenient point.

Having thus described my invention, what I claim and desire to secure by Letters Patent is—

In an umbrella locker, the combination 10 with an appropriate receptacle of a hinged cover therefor, a sliding bolt on the under-side of the cover and adapted when moved in one direction to engage a detent to prevent the cover opening, a spring-pressed

bolt mounted adjacent to the hinges of the 15 cover and independent of the cover and in line with the bolt and operative to project the bolt into locking engagement with the detent, a locking bolt for the spring pressed bolt and means for releasing the last named 20 locking bolt.

In testimony whereof I have hereunto set my hand in the presence of two subscribing witnesses.

WILLIS S. FARNSWORTH.
